Inventor

14th Samuel R. Farnum

Robert Young Attorney

UNITED STATES PATENT OFFICE.

SAMUEL R. FRAIM, OF LANCASTER, PENNSYLVANIA.

PADLOCK.

Application filed May 28, 1924. Serial No. 716,401.

To all whom it may concern:

Be it known that I, SAMUEL R. FRAIM, a citizen of the United States, residing at Lancaster, in the county of Lancaster and State of Pennsylvania, have invented certain new and useful Improvements in Padlocks, of which the following is a specification.

This invention relates to improvements in the class of locks, generally referred to as padlocks, and pertains more particularly to locks for the throttle and spark control for automobiles, rear spare tire carriers, for plain rims, and disc wheels in which a removable shackle is employed to embrace said parts of the automobile control.

An object of my invention is to provide a padlock, of the nature described, embodying a shackle and locking members for automatically locking the parts when the shackle is inserted in the proper end of the casing, namely, the end opposite to that in which the key plug is located.

Another object of my invention is to provide a locking mechanism in which it will be impossible to insert the shackle in improper position in such a manner that the shackle would interfere with the placing of a key in the proper end for unlocking, which comprises a distinct advantage in locks of the character referred to, and avoids the disadvantages incident to such locks not thus equipped.

A further object of my invention is to produce a lock of the nature described in which the desired results are accomplished by a minimum number of associated parts in a more simple, cheap, and efficient combination than has heretofore been attained.

A still further object is to provide a padlock in which the locking mechanism shall consist in locking bolts being snugly fitted in the casing so as to provide for lateral and prevent longitudinal movement, the locking bolts being parallel and having their extremities in the same lateral plane to insure against forcible opening of the padlock by equally distributing the resistance to shock.

With the foregoing and other objects in view, my invention consists in the combination and arrangement of associated parts and in the details of construction herein-after described and more particularly pointed out in the claims; certain embodiments

being illustrated in the accompanying drawings, in which:

Figure 1 is a plan view of the padlock with the upper parts of the casing removed, showing the shackle in locked position and the key inserted, in dotted lines; 60

Figure 2 is a similar view showing the shackle partially inserted in the improper manner and abutting the protruding flat ends of the locking bolts to illustrate the 65 impossibility of locking the shackle in improper position;

Figure 3 is a bottom plan view of the padlock with the shackle withdrawn, showing the bolts protruding into the shackle 70 channels in the casing;

Figure 4 is a view in section taken along lines 4—4 of Figure 2;

Figure 5 is a bottom plan view in detail of the locking bolts and their resilient actuating members; 75

Figure 6 is a detail view in end elevation of one of the bolts, showing the hole in the end and a depression in its extension for the reception of the two spring actuating 80 members;

Figure 7 is a view similar to Figure 5, showing the key bearing on the shoulders of the bolts, the latter being in retracted and unlocked position. 85

Referring more particularly to the drawings the casing consists of an upper and lower portion 1 and 1'. The lower half 1' is provided with cross ribs 19, 18, 17, and 12 and a plurality of rivets 20 for connecting the two halves of the casing together. The casing is further provided with channels 16 and 16' extending throughout both ends 21 and 22 of the casing and through the intermediate cross ribs above referred to. 90

The shackle is preferably U-shaped and has its legs 2 and 3 provided with a plurality of notches such as shown at 2' and 3' the legs 2 and 3 also having their extremities bevelled at 26 and 26'. 95

The locking mechanism for the padlock is automatic in its operation and consists mainly in a pair of opposed angular locking bolts, arranged between the ribs 17 and 18 of the casing, and adapted to slide laterally upon each other in overlapping relation in such a manner as to engage the shackle in locked relation. Each of the bolts 4 and 5 is provided with a central cut-out portion 23 and 24, respectively through which the 100 105 110

key 15 is inserted; and, as shown in detail in Figures 5 and 7, the bolts 4 and 5 are provided with shoulders 23' and 24', respectively, extending into the cut-out portions 23 and 24 and arranged oppositely against which the key is engaged to simultaneously retract the bolts from engagement with the notches 2' and 3' of the shackle legs 2 and 3.

10 The rotation of the key to retract the bolts out of locked engagement with the shackle is accomplished against the action of spring actuated mechanism for normally and automatically distending the bolts and 15 locking the shackle. This spring means consists in a compression coil spring 6, located in a channel 14 in the end of the bolt 4, forcing a rod 7 into a corresponding depression 13 in the angular overlapping 20 and upwardly extending extension 5' of the bolt 5; while in the hole 14' in the end of the bolt 5 is located a spring 8 adapted to force a rod 9 into a corresponding depression 13 in the angular overlapping and downwardly 25 extending extension 4' of the bolt 4. This enables the bolts 4 and 5 to be normally spring-actuated in an outward and opposite direction, the springs being interposed between and bearing upon the bolts alone to 30 force them outwardly into locking position.

A key plug 10 is rotatably and removably mounted on the rib 19 of the casing to receive a key 15 in the key plug slot 11. The key 15 is provided with notches 28, 29 and 30 and a tip 27 registering with the ribs 12, 17 and 18 and the depression 26 of the casing, respectively, in such a manner that the key when properly inserted may be rotated without interference and also rotate the key plug 10, therewith. The key when thus inserted and rotated in the proper direction, engages the shoulders 23' and 24' of the bolts 4 and 5, retracts the bolts upon each other out of engagement with the notches 2' and 3' of the shackle and out of the channels 16 and 16', against the action of the springs 6 and 8, and allows the shackle to be readily withdrawn from the casing.

50 The bolts 4 and 5 besides being arranged in parallel and overlapping position between the ribs 17 and 18, are fitted snugly but slidably therein, and have their flat edges which engage the notches 2' and 3' of the shackle legs 2 and 3 in the same plane. 55 This arrangement insures against a forcible opening of the lock without using the proper key as any pressure exerted on the shackle will be equally distributed to both bolts and the bolts are prevented from longitudinal movement by reason of their close engagement by the ribs of the casing.

In order to lock the device it is only necessary to insert the shackle in the end 22 of the lock as shown in Figure 1, the 60 bevelled edges 26 and 26' of the shackle

legs 2 and 3 providing for a ready insertion of the shackle. The extension 4' and 5' of the bolts 4 and 5, being spring actuated, engage the notches 2' and 3' of the shackle legs 2 and 3, and retain the shackle in locked position. The bevelled or curved edges on the bolts allows the corresponding bevelled edges 26 and 26' of the shackle to be readily inserted in the end 22 of the lock past the bolts which lock the shackle, the key slot 70 being arranged in the opposite end 21. When thus properly locked and the shackle inserted in the manner described, the key may be applied without interference with the shackle. If, however, the shackle were inserted in the end 21 of the padlock by inadvertence, it will be readily seen that the curved portion of the shackle would be in such a position adjacent the key plug that it would be impossible to insert the key. 75 Thus the device could not be unlocked and the same would have to be disassembled in order to remove the shackle.

80 In order to guard against such a situation the angular extensions 4' and 5' of the locking bolts 4 and 5 have only their upper sides bevelled or curved while their lower extremities are flat and normally extend into path of the shackle in the channels 16, in order to render it impossible to insert the shackle in the improper manner far enough 85 to be engaged in locked relation.

90 Thus it will be seen that there has been provided a removable-shackle padlock consisting in the minimum number of easily and cheaply manufactured parts readily assembled, disassembled, and replaced with the maximum of ease. There has also been provided a padlock with the most efficient and 95 simple mechanism for automatically locking a shackle when properly applied, and for positively preventing the insertion and locked engagement of a shackle when improperly applied to the padlock.

100 The construction of the locking bolts in overlapping relation, when the spring actuation members so arranged that they extend between the component parts of the bolts, bearing upon these parts alone, provides 105 for an effective mechanism for keeping the bolts in outwardly distending locking position. This avoids the use of more complicated locking mechanism, such as tumblers and the like, and at the same time guards against malfunction of its parts.

110 An improved means for unlocking has also been provided by the construction of a key plug adapted to rotate with the key, and the provision of locking bolts with such 115 portions that the key when rotated engages shoulders of the bolts incident to such cut-out portions in such a manner as to slide the bolts upon each other and withdraw them from engagement with the shackle. 120 The arrangement of the locking bolts in 125 130

snug relation with and between lateral ribs of the casing, the bolts being parallel and overlapping so that the locking extremities engaging the shackle are in the same lateral plane, provides for an equally distributed resistance to shock and insure against a forcible and unauthorized opening of the padlock.

I claim—

- 10 1. A padlock comprising a casing provided with channels to receive a shackle, a pair of spring actuated locking bolts, said bolts having angular extensions, bevelled on their upper and flat on their lower sides and adapted normally to protrude into said channels, each of said bolts having a spring 15 plunger mounted in one end and bearing on the angular extension of the other bolt, one of said extensions extending upwardly and the other downwardly, said bolts being 20 and the other downwardly, said bolts being

adapted to slide upon each other and engage said shackle in locked relation.

2. A padlock comprising a casing provided with channels to receive a shackle, a pair of spring-actuated locking bolts arranged parallel between ribs of said casing, said bolts having angular extensions, bevelled on their upper and flat on their lower sides and adapted normally to protrude into said channels, each of said bolts having a spring 25 plunger mounted in one end and bearing on the angular extension of the other bolt, one of said extensions extending upwardly and the other downwardly, said bolts being adapted to slide upon each other and engage 30 said shackle in locked relation.

In testimony whereof I affix my signature.

SAMUEL R. FRAIM.
